(57) **CLAIM**

We claim the design for a vanity, as shown and described.

DESCRIPTION

FIG. 1 is an upper front right perspective view of a vanity design;

FIG. 2 is an upper front left perspective view of the vanity design of FIG. 1;

FIG. 3 is a top plan view thereof;

FIG. 4 is a front elevational view thereof;

FIG. 5 is a left elevational view thereof;

FIG. 6 is a right elevational view thereof;

FIG. 7 is a bottom plan view thereof;

FIG. 8 is a rear elevational view thereof, the dashed lines being unclaimed;

FIG. 9 is a cross sectional view of the vanity design taken along line 9-9 in FIG. 3, the dashed lines being unclaimed; and,

FIG. 10 is a cross sectional view of the vanity design taken along line 10-10 in FIG. 3, the dashed lines being unclaimed.
